UNITED STATES PATENT OFFICE

94,973

DESIGN FOR AN AMUSEMENT GAME APPARATUS

Charles E. Hoagland, Los Angeles, Calif., assignor to The Exhibit Supply Company, Chicago, Ill., a corporation of Illinois

Application January 21, 1935, Serial No. 54,967

Term of patent 3½ years

To all whom it may concern:

Be it known that I, Charles E. Hoagland, a citizen of the United States, residing at Brentwood Heights, Los Angeles, in the county of Los Angeles and State of California, have invented a new, original, and ornamental Design for an Amusement Game Apparatus, of which the following is a specification, reference being had to the accompanying drawing forming part thereof, and in which:

The single figure is a perspective view showing the new design.

I claim:

The ornamental design for an amusement game apparatus as shown.

CHARLES E. HOAGLAND.
